UNITED STATES PATENT OFFICE.

GEORGE F. HUTCHINGS, OF KANSAS CITY, MISSOURI.

MANIFOLDING DEVICE.

954,102.

Specification of Letters Patent.

Patented Apr. 5, 1910.

Application filed October 10, 1908. Serial No. 457,068.

To all whom it may concern:

Be it known that I, GEORGE F. HUTCHINGS, a citizen of the United States, residing at Kansas City, in the county of Jackson 5 and State of Missouri, have invented certain new and useful Improvements in Manifolding Devices, of which the following is a specification.

My invention relates to improvements in 10 manifolding devices for duplicating writing on record sheets, receipt cards, &c., and the invention embraces a holder for securing the record sheets and the receipt cards in proper relation to each other preparatory to 15 being written on, a primary clamping member which assists the holder in securing the record sheets and the receipt cards in proper relation to each other, a secondary clamping member which assists the primary clamping 20 member in holding the record sheets after they have been written on, and a base to which the holder and the primary clamping member are secured, and which also affords an arm-rest for the clerk who fills in the 25 record sheets and the receipt cards.

The device is particularly adapted for use in the registry department of the postal service, as by its use considerable time can be saved in filling in receipt cards, and record sheets of the same.

The device may also be employed to advantage as a temporary file for holding the filled-in record sheets until a sufficient number have accumulated to warrant their permanent filing.

In order that the invention may be fully understood, reference will now be made to the accompanying drawing, in which:

Figure 1 represents a perspective view of 40 the invention. Fig. 2 represents a central vertical section of the invention.

In constructing the device I employ a base 1, which is of sufficient length to afford an arm-rest for the clerk while filling-in the 45 record sheets and the receipt cards. The intermediate portion of said base is provided with a holder for securing the record sheets A and the receipt cards in proper relation to each other. Said holder consists of 50 a bottom portion 2, and marginal flanges 3 and 4, which latter is considerably lower

than the former, to avoid interfering with the clerk's hand when filling in the record sheets and the receipt cards. Flange 4 is cut out at its central portion 4^a, and a depression 5 is formed in the base beneath said cut-out portion, so that the clerk may insert his thumb beneath each record sheet preparatory to removing the same from the holder after it has been filled in.

The holder is assisted in securing the sheets and the cards in proper relation to each other by a pair of pins 6, projecting upwardly from the base. The holder is further assisted in securing the sheets and the cards in position by a primary clamping member 7, which is pivotally-mounted upon the base, it being provided with rearwardly-turned ears 8, which are pivotally secured to a pair of ears 9, secured to the upper portion of the base. The primary clamping member 7 also acts as a file in holding the record sheets after they have been filled in, and for that purpose it is provided with marginal flanges 10, and a secondary clamping member 11, which latter is pivotally-secured to a pair of ears 12, projecting forwardly from a handle 13 of the primary clamping member. The lower ends of the clamping members 7 and 11 are held down 80 upon the sheets by springs 14 and 15, respectively.

In practice the holder is supplied with a number of receipt cards, record sheets, and a carbon sheet, and after a record sheet has 85 been filled in, its upper end is left below the primary clamping member while its lower free end is turned upward and placed beneath the secondary clamping member 11, as shown in Fig. 2. Each succeeding record 90 sheet, after being filled in, is disposed of in the same manner until a sufficient number have accumulated to warrant their being permanently filed away.

Having thus described my invention, what 95 I claim is:—

A device of the character described consisting of a base, a holder secured to the intermediate portion of said base and provided with marginal flanges for holding 100 sheets and cards in proper relation to each other, a primary clamping member mounted

on the base above said holder to assist in holding the sheets and cards, said clamping member being provided with marginal flanges to protect the edges of the sheets
5 when turned back upon said member, and a secondary clamping member mounted near the upper end of a primary clamping member to assist in holding the sheets turned

back upon said primary clamping member, substantially as described. 10

In testimony whereof I affix my signature, in the presence of two witnesses.

GEORGE F. HUTCHINGS.
